SOLE ROUGHING MACHINE

Angelo Perri, Groveland, Mass., assignor to Allied
Shoe Machinery Corp., Haverhill, Mass., a cor-
poration of Massachusetts

Application October 16, 1946, Serial No. 703,535

9 Claims. (Cl. 69—1)

1

This invention relates to improvements in roughing machines and more particularly machines for roughing the marginal region of a shoe sole element preparatory to cementing the element in place in a shoe structure.

It is among the objects of the invention to provide a roughing machine wherein the work, such as a shoe sole, is automatically fed and guided to advance a marginal region of the work progressively to roughing position, all around the edge of the work, and wherein the roughing is accomplished by the action of roughing elements travelling generally in the plane of the surface which is being roughed.

Another object is to provide a roughing machine for roughing a marginal region of a work element, all around the element, and having provision for leaving an un-roughed narrow band at the extreme edge of the work element.

Yet another object is to provide a sole element roughing machine having a pair of feed wheels rotating in opposite directions on angularly related axes with a pair of guides for the edges of the sole element against both of which the sole element is urged edgewise by the feeding coaction of the angularly related wheels and against one of which the sole element is additionally urged edgewise by a roughing member rotatably engaging the marginal region of the sole element as the element is advanced between the feed wheels.

A further object is to provide a sole element roughing machine having a pair of work feeding wheels rotating in opposite directions on angularly related driving shafts of which one is adjustably biased toward the other for engaging the margin of a sole element between them, with the angularly related wheels coacting for advancing the work and with one wheel urging the sole element laterally simultaneously with its advance.

Still another object is to provide a sole element roughing machine having means for roughing a marginal region of a sole element, and including means for adjustably spacing the roughed area inward from the edge of the sole element.

It is, moreover, my purpose and object generally to improve the structure and effectiveness of roughing machines and more especially machines for roughing the marginal regions of shoe sole elements.

In the accompanying drawings:

Fig. 1 is a front elevation of a roughing machine embodying features of my invention;

Fig. 2 is a top plan view of the machine of Fig. 1;

2

Fig. 3 is a cross-sectional view approximately on line 3—3 of Fig. 2;

Fig. 4 is a cross-sectional detail, on a larger scale, of the adjustable roller which engages under the work;

Fig. 5 is a cross-sectional view approximately on line 5—5 of Fig. 1, on a larger scale;

Fig. 6 is an enlarged cross-sectional detail of one of the adjustable guide rollers which engage the edge of the work;

Fig. 7 is a perspective view, somewhat diagrammatic, of one of the pivoted roller-carrying arms which engage the upper surface of the work;

Fig. 8 is a bottom plan view of a shoe sole element having its marginal region roughed, and showing a narrow band of un-roughed surface at the extreme edge of the element;

Fig. 9 is a fragmentary cross-sectional view on line 9—9 of Fig. 8; and

Fig. 10 is a detail cross-sectional view through the work at the roughing position, and showing a sole element having a skived upper marginal surface.

Referring to the drawings, any suitable support 10 may serve for mounting the hollow casing 12 from which the relatively large diameter conduit 14 leads to a suitable suction means (not shown) which creates a partial vacuum in casing 12 for removing dust and waste matter from the region where a marginal portion of a sole element is roughed by means and in a manner which presently will be described.

Casing 12 includes the upper rectangular relatively shallow portion 16 within which the shaft 18 extends, with a feed wheel 20 on the forward end of the shaft for engaging the under margin of a sole element S. The portion 16 of the casing has a top opening which is closed by a removable cover plate 22, and this plate 22 constitutes the work support at the roughing region and has a relatively large slot 24 through which feed wheel 20 operates to engage the work.

Toward the rear of the machine, the shaft 18 has universal connection at 26 to a short shaft 28 which extends into and is journaled in the walls of a gear housing 30 suitably mounted at the rear end of the casing. Short shaft 28, interiorly of housing 30, has fixed thereon a worm gear 32 meshing with a worm 34 on a shaft 36 which extends out of housing 30 and which has a pulley 38 on its outer end. An electric motor 40 is pivotally supported on casing 12 at 42 and is adjustable on pivot 42 by means of the adjusting screw 44. The motor shaft 46 has a pulley 48

thereon for driving worm 34 through the medium of belt 50.

The extreme forward end of shaft 18 is mounted in the adjustable eccentric bearing 52, as best seen in Fig. 3, the bearing having an annular groove 54 within which the set screw 56 engages for securing the bearing against axial displacement and by which the bearing may be fixed in any adjusted setting, the bearing having a knurled head 58 by which it may be manually rotated when the set screw 56 is loosened. With this construction, the forward end of shaft 18 may be raised or lowered for precision setting of the feed wheel 20, the universal connection at 26 permitting needed adjustments at the forward end of shaft 18 without interfering with the drive of the shaft 18.

A feed wheel 60 is positioned for coaction with feed wheel 20 in feeding a sole element S engaged between them. Wheel 60 is fixed on the forward end of a shaft 62 whose rear end has a universal connection at 64 to a short shaft 66 which is similar to short shaft 28 and which has the worm gear 68 fixed thereon interiorly of housing 30 and meshing with the worm 34, whereby shaft 62 is rotated in direction opposite to the direction of rotation of shaft 18.

It is a feature of the invention that the shaft 62 has its forward portion extending through a bearing 70 at the forward end of an arm 72 which is pivotally mounted at 74 on ears 76 which are rigid on the gear housing 30. Arm 72, at its rear end, has an ear 78 rigidly upstanding thereon in which the two-diameter pin 80 is rotatably mounted, with the larger diameter portion 80' at one side of the ear and with the smaller diameter portion 80'' extending through and projecting at the other side of the ear.

A rigid upstanding ear 82 on gear housing 30 is in general alignment with ear 78 on arm 72, and has rotatably mounted therein the two-diameter pin 84 with the larger diameter portion 84' at one side of the ear and with the smaller diameter portion 84'' extending through and projecting at the other side of the ear. Two screws 86, 88 each extends through both of the pins 80, 82 at a different side of the ears 78, 82. Screw 86 extends slidably through pin 80 and is threadedly engaged through pin 84, while screw 88 is threadedly engaged through pin 80 and slidably engaged through pin 84. A nut 90 is adjustable on screw 86, between the pins, and a spring 92 engages between the nut and pin 80, constantly biasing the arm 72 clockwise about its pivot 84, as viewed in Figs. 1 and 3, and the limit of clockwise movement of the arm is adjustably determined by the enlarged portion 89 of screw 88, at its head end, engaging the pin 84. Hence, mere rotation of screw 88 effects adjustment of arm 72 to bring feed wheel 60 closer to or further from the coating feed wheel 20. However, the arm 72 is resiliently yieldable, against the bias of spring 92, in direction generally away from the wheel 20.

As clearly shown in Figs. 1 and 3, the shaft 62 may have considerable inclination relative to the generally horizontal shaft 18, and the periphery of wheel 60 is tapered so that its engagement with a sole element may be a generally horizontal engagement notwithstanding the inclination of shaft 62. Wheel 20, on the other hand, preferably will have a generally cylindrical periphery with oblique teeth therein for urging the work laterally simultaneously with the advance of the work between the wheels, with the lateral thrust

augmented to a substantial degree by the fact that the two work-engaging wheels rotate in opposite directions on angularly related axes.

A sole element S inserted between wheels 20, 60 is engaged at a marginal region of the element, and the course of the element is determined by the pair of guide rolls 94, 96 which engage the edge of the element as the latter advances between the wheels. Roll 94 may be arranged generally opposite the peripheries of the feed wheels so that the main forward advance of the work thrusts the edge of the work against roll 94. The other roll 96 may be positioned generally laterally beside the region of bite of the wheels, and the previously described lateral thrust on the work maintains the edge of the work against roll 96. As a result, after a sole element has been initially engaged between wheels 20, 60, it feeds automatically with the wheels engaging progressively all around the margin of the sole element.

According to the invention, a sole element feeding between the wheels 20, 60 is roughed at the under side progressively all around the margin of the upper by a toothed roughing member whose teeth rotate in a plane generally parallel with the work surface which is being roughed. Referring more particularly to Figs. 3 and 5, a roughing member is indicated generally at 98, secured on the upper end of a vertical shaft 100 which is mounted in a yoke 102 and which has a pulley 104 thereon, within the yoke, belt driven from an electric motor 106. Roughing member 98, as shown, has generally cylindrical form, with its annular top edge provided with the cutting teeth or serrations 108. Member 98 is removably mounted on shaft 100 by means of the screw 110 projecting from the shaft and engaging in the bayonet slot 112 in member 98. Yoke 102 has bosses 114, 116 projecting from the respective arms of the yoke which provide bearings for shaft 100. The upper boss 114 projects slidably through the bottom wall of the forward portion of the casing, and the lower boss 116 is slidably supported in a bracket 118 which is secured to this bottom wall of casing, as best seen in Fig. 5. A groove 120 in the bracket loosely receives a peripheral portion of the head 112 of an adjusting screw 124 which is threaded into yoke 102, with a pair of pins 126 projecting from the bracket on opposite sides of the shank of the screw for steadyng the latter. Rotation of the screw, with its head 122 restrained against vertical travel, effects adjustment of the yoke and of roughing member 98 toward or from the work to increase or decrease the roughing effect. By providing a split bearing for the boss 116 of yoke 102, the yoke may be clamped in any adjusted position by tightening the split-bearing by means of screw 119.

The roughing member 98 operates in the slot 24 in the cover-plate work support 22. Its position inward relative to guide roll 96 and outward relative to guide roll 94, as best seen in Fig. 2, and the direction of its rotation, as indicated by the arrow in Fig. 2, combine to create a relatively strong tendency to rotate the work about the axis of the roughing member 98, and this tendency urges the edge of the work in direction toward guide roll 96. The incidental tendency to swing the work away from guide roll 94 is over-borne by the action of the feed wheels 20, 60 whose main feeding effect is toward the guide roll 94. The cumulative effect of the feed wheels and roughing member on the work is to maintain the edge of the work strongly against guide roll 96 and against

guide roll 94, but with the roughing member acting with roll 94 in guiding the leading portion of the work.

Inasmuch as the roughing member 98, working on the under side of the work, tends to lift the work away from support 22, I provide one or more spring-biased arms 128, each with a roller 130 at its end, for riding on the upper surface of the work and pressing the work against support 22 in opposition to the lifting tendency of member 98. As herein shown, two such arms 128 are pivotally mounted on a bracket 132, each with a spring 134 adjustably biasing its roller carrying end into engagement with the work. Fig. 7 shows one of the arms 128 with a laterally projecting lug 136 thereon through which a screw 138 loosely extends for screwing into the bracket 132. The spring 134 engages between the head of the screw and the lug 136, constantly biasing the arm and roller 130 clockwise in Fig. 7. The biasing force may be adjusted by means of screw 138. Another screw 140 is threaded through lug 136 with its lower end butted against bracket 132, for adjustably limiting the clockwise movement of arm 128, with a lock nut 142 for locking screw 140 in any particular adjusted setting. With this construction, the rollers 130 effectively press the work against support 22 when the upper and lower surfaces of the engaged work are parallel and also when the upper surface is skived, as suggested in Fig. 10.

Preferably, also, I provide a roller 144 (Figs. 3 and 4) for engaging the under side of the work adjacent to the roughing member 98, thereby to avoid any possibility of an edge of the work getting caught in the slot 24 when being introduced between the feed wheels. As best seen in Fig. 4, this roller 144 is conveniently carried at the end of an arm 146 which is pivoted at 148 on the under side of cover plate 22, with an adjustable screw 150 threaded through the arm and resting by gravity on a wall of the casing. The roller engages the work through the slot 24, and may be adjusted as to position by means of screw 150.

It is an important feature of the invention that a marginal region of a sole element may be quickly and effectively roughed all around the sole element without roughing the extreme edge of the element which may be exposed in a shoe. In cemented shoes, the sole elements frequently are formed to accurate shape prior to combining with an upper, so that the sole elements require no subsequent trimming or grinding. In such cases, it becomes important that the edges which are to be exposed in a shoe shall be smooth and finished. My present roughing machine is adapted to effectively rough a desired marginal region of a sole element while leaving a desirable bead or thin band of un-roughed surface at the extreme edge of the element, as represented in Figs. 8 and 9, where the roughed band is indicated at 152 and a narrow un-roughed bead or band is indicated at 154. With my rotary roughing member 98 acting on the work in a generally horizontal plane, the guide roll 94 may be set close to the circle of roughing action of member 98 for determining a width of edge surface which will not be roughed. In this connection, it should be noted that the roller 94 is mounted for minute adjustment relative to member 98. Fig. 6 shows roller 94 mounted on an eccentric bearing 156 which is mounted on cover plate 22 by means of a screw 158. By loosening screw 158 the eccentric 156 may be rotated to bring the periphery of the roller toward or from the peripheral circle of

roughing member 98, thereby to vary the width of the un-roughed bead or band 154. Tightening of screw 158 secures the roller in any selected setting. The other roller 96 may be similarly eccentrically mounted for adjustment, if desired.

I claim as my invention:

1. A roughing machine comprising a work support having an opening therethrough at the roughing position, a rotary roughing member mounted on an axis generally perpendicular to the work support and operating in said opening in the work support for engaging and roughing the under surface of work resting on the support, a pair of coaxing feed wheels mounted on angularly related axes and arranged for engaging a marginal region of the work, means driving the feed wheels in opposite directions for advancing the work past said roughing member, and a pair of guides for engaging edge portions of the work and arranged for guiding the course of the work, said roughing member rotating in direction to constantly urge the work edgewise against at least one of said guides.
2. A roughing machine comprising a work support having an opening therethrough at the roughing position, a rotary roughing member mounted on an axis generally perpendicular to the work support and operating in said opening in the work support for engaging and roughing the under surface of work resting on the support, a pair of coaxing feed wheels mounted on angularly related axes and arranged for engaging a marginal region of the work, means driving the feed wheels in opposite directions for advancing the work past said roughing member, and a pair of guides for engaging edge portions of the work and arranged for guiding the course of the work, said roughing member rotating in direction to constantly urge the work edgewise against at least one of said guides, said roughing member rotating in direction to constantly urge the work edgewise against at least one of said guides, and one of said feed wheels being adjustably biased in direction generally toward the other feed wheel.

3. A roughing machine comprising a work support having an opening therethrough at the roughing position, a rotary roughing member mounted on an axis generally perpendicular to the work support and operating in said opening in the work support for engaging and roughing the under surface of work resting on the support, a pair of coaxing feed wheels mounted on angularly related axes and arranged for engaging a marginal region of the work, means driving the feed wheels in opposite directions for advancing the work past said roughing member, a pair of guides arranged in spaced relation outward from said roughing member for engaging edge portions of the work and guiding the course of the work as it is advanced by the feed wheels, and means for setting one of said guides toward and from said roughing member for selectively predetermining a width of surface adjacent to the edge of the work inward of which the roughing by said roughing member will occur, thereby to leave said predetermined width free of any roughing.

4. A roughing machine comprising a work support having an opening therethrough at the roughing position, a rotary roughing member mounted on an axis generally perpendicular to the work support and operating in said opening in the work support for engaging and roughing the under surface of work resting on the support, means for adjusting said roughing member toward and from the work to vary its roughing effect on the work, means pressing the work against said roughing member, a pair of driven

feed wheels rotating in opposite directions on angularly related axes and engaging a marginal region of the work outward of said roughing member, a pair of guides outward of said feed wheels for engaging edge portions of the work thereby to guide the course of the work advancing between the feed wheels, said roughing member rotating in direction to constantly urge the work edgewise against one of said guides, and means for adjusting the other guide toward and from the roughing member for selectively locating the roughing any of various distances inward from the edge of the work.

5. In a roughing machine having a work support and a pair of coacting feed wheels driven in opposite directions for advancing a work element between the wheels, the combination therewith of a roughing member rotating on an axis generally perpendicular to the work support, there being an opening in the work support within which said roughing member operates with an end portion thereof rotarily engaging an under region of the work in a plane generally parallel with the plane of the work support whereby said roughing member tends to rotate the work about the axis of the roughing member, an edge guide arranged to restrain said rotational tendency of the work, and another edge guide generally in the path of the work for swinging the work about the first guide as an axis, thereby to guide the course of the work advancing between said wheels.

6. In a roughing machine having a work support and a pair of coacting feed wheels driven in opposite directions for advancing a work element between the wheels, the combination wherein one of said wheels is mounted on an axis angularly related to the axis of the other wheel, whereby a work element feeding between the wheels is urged laterally simultaneously with its advance between the wheels, a guide roller in the path of advance of the work for engaging an edge portion of the work, said lateral urge maintaining said edge against the roller, a roughing member rotating on an axis perpendicular to the work support with an end portion thereof rotarily engaging the work and tending to swing the work away from said guide roller, and a second guide roller opposing the latter said swinging tendency of the work and constituting a fulcrum of swinging of the work as the first said guide roller directs the course of the work advancing between the feed wheels.

7. In a roughing machine having a work support with an opening therethrough, the combination therewith of a roughing member rotating on an axis perpendicular to the support with an end

projecting through said opening into contact with a work element on the support, said contacting end of said member being adapted to rough the engaged surface portion of the work, a driven feed wheel rotating on an axis generally parallel with the work support and engaging a surface of the work through said opening, a second driven feed wheel rotating in direction opposite to the direction of rotation of the first said feed wheel and on an axis inclined with respect to the axis of the first wheel, means for varying the inclination of the axis of the second wheel, and a pair of guides for engaging edge portions of the work thereby to direct the course of the work element advancing between the feed wheels, said second wheel urging the work laterally toward at least one of said guides simultaneously with the main advance of the work.

8. In a roughing machine, a work support having an opening therethrough at the roughing position, a roughing member rotating on an axis perpendicular to the support with an end portion projecting through said opening for contacting and roughing a work element on the support, a pair of oppositely driven shafts, each having a universal drive connection whereby an end of each shaft may be adjusted about its universal connection, a feed wheel on the adjustable end of each shaft for coaction in feeding a work element between them, means resiliently biasing one said wheel toward the other, the wheel-supporting end of one of said shafts being inclined relative to the wheel supporting end of the other shaft whereby the wheel on said inclined shaft urges the work laterally simultaneously with its advance between the wheels, and guide means engaging edge portions of the work element, at least one of which is positioned to have the work urged thereagainst by said wheel tending to urge the work laterally.

9. In a roughing machine, a work support having an opening therethrough at the roughing position, a roughing member rotating on an axis perpendicular to the support with an end portion projecting through said opening for contacting and roughing a work element on the support, a pair of oppositely driven shafts, each having a universal drive connection whereby an end of each shaft may be adjusted about its universal connection, a feed wheel on the adjustable end of said shafts for coaction in feeding a work element between them, and means for independent adjustment of each wheel toward and from the other, said adjustment for one wheel including biasing means constantly pressing that wheel in direction toward the other wheel.

ANGELO PERRI.
